CLAIM

The ornamental design for a shelf for corner, substantially as shown and described.

DESCRIPTION

FIG. 1 is a top, front perspective view of the shelf for corner. FIG. 2 is a top, left perspective view of the design of FIG. 1.

FIG. 3 is a top, right perspective view of the design of FIG. 1.

FIG. 4 is a top, rear perspective view of the design of FIG. 1.

FIG. 5 is a front elevational view of the design of FIG. 1. FIG. 6 is a left side elevation view of the design of FIG. 1. FIG. 7 is a right side elevation view of the design of FIG. 1. FIG. 8 is a bottom, rear perspective view of the design of FIG. 1.

FIG. 9 is a top view of the design of FIG. 1; and, FIG. 10 is a bottom view of the design of FIG. 1.

The portions of the figures shown in broken lines illustrate features of the shelf for corner that do not form part of the claimed design.

1 Claim, 5 Drawing Sheets
